UNITED STATES PATENT OFFICE.

SAMUEL BLACKETER, OF GOWRIE, IOWA.

MUSICAL INSTRUMENT.

SPECIFICATION forming part of Letters Patent No. 552,862, dated January 7, 1896.

Application filed December 8, 1894. Serial No. 531,269. (No model.)

To all whom it may concern:

Be it known that I, SAMUEL BLACKETER, a citizen of the United States, residing at Gowrie, in the county of Webster and State of Iowa, have invented certain new and useful Improvements in Musical Instruments; and I do hereby declare the following to be a full, clear, and exact description of the invention, such as will enable others skilled in the art to 10 which it appertains to make and use the same.

In playing musical instruments in which the hands are used—as the violin, mouth-organ, &c.—it is often very desirable to have some instrument on which an accompaniment 15 can be played, and which can best be done by the feet. Heretofore it has been common to have the feet operate such instruments as a drum or cymbal, in which but a single tone was produced, but such instruments are not 20 always desirable. By the use of my invention, however, it is not only possible to produce different tones, but also possible to play an accompaniment in any one of several different keys.

25 Although I have shown the invention as applied to one style of stringed instruments, it is evident that it could be adapted for other forms or to other kinds of instruments. By its use the performer can play an accompaniment by the use of the feet, thus leaving the arms and hands free for performing upon the main instrument.

In the accompanying drawings, in which the same reference-numerals indicate corresponding parts in each of the views in which they occur, Figure 1 is a face view of the boards to which the beaters are secured. Fig. 2 is a perspective view of the instrument. Fig. 3 is a vertical sectional view, and Fig. 4 30 a plan of the dulcimer.

40 Referring more particularly to the drawings, 1 indicates the case of the instrument, within which is secured the stringed portion 2, which is preferably in the form of the dulcimer. The dulcimer is made hollow with the ordinary sounding-board, upon which are placed the bridges 3 and 4. The bridge 3 divides the instrument transversely of the strings into the bass and treble, and the 45 bridges 4 are placed to one side of the central bridge. Each of the bridges is provided with holes or openings 5, through which a

portion of the strings pass, so that a portion of the strings may pass over the tops of some of the bridges and through the openings of the others, and cross intermediate the bridges and thereby be arranged to sound different tones without interfering with each other.

55 Arranged within the case parallel with the front of the instrument are two boards 6 and 7, on which the beaters are arranged, so that the free ends of the beaters may be caused to strike the desired strings and thereby produce the desired tones. One of these boards is provided with the beaters for the treble or 60 upper notes, and the other one is provided with those for the bass. As it generally requires three tones to produce the chord for the treble, those beaters are made larger than the bass beaters, so that the three arms 8 can 65 be secured on the rock-bars 9 without interfering with each other. These rock-bars are pivoted in suitable bearings 10 on the board, and are arranged in any desired manner, generally one above or in front of the other, as 70 shown in the drawings.

75 The free end of each of the arms is provided with a head or hammer which is adapted to strike its respective string when operated and cause it to vibrate and produce the desired 80 sounds. By making the arms of different lengths it is evident that when the rock-bar is turned on its pivot all of the hammers of that beater will be thrown against their respective strings and cause them to vibrate in 85 unison. For the purpose of operating these beaters by means of the feet I provide pedals 11, which are pivotally secured at the bottom of the frame, with one end projecting outside and the opposite end located within the case 90 and provided with the hook 12 or other means, to which is secured a cord or chain 13, the opposite end of said cord being connected with the rock-shaft of the beater.

95 Intermediate the pedals and the beaters are located pulleys 14 over which the cords pass, so that when the outer end of any one of the pedals is pressed down by the foot its cord will be drawn over the pulleys and thereby rotate the rock-shaft on its pivot and cause 100 the hammers to strike the strings. A suitable spring 15 or other means is provided for returning each of the beaters to its original position after the pressure on the pedal has

been removed. As only a few of the beaters are used in playing the chords in any key, it is not necessary to provide a pedal for each beater, but only enough pedals for the number of beaters that will be used in that key. 5 To make the pedals and beaters interchangeable, as it were, I prefer to detachably secure the cord to the pedal so that it can be removed at any time and another cord put in its place. For this purpose I provide the end of each cord with a series of links 16, which may be passed over the hook and may also be secured to hooks 17 on the rear of the boards 6 and 7 when not in use. By using a 15 sufficient number of links the proper tension of the cords can always be secured, even though they should stretch to a greater or less extent in use. For the sake of convenience I prefer to letter each one of the hooks on the boards 6 and 7, with the letters indicating the chord which will be struck by the different beaters, and then securing the end of the cord when not in use from each beater on its respective hook. 20 25 In the drawings I have shown an instrument adapted for playing accompaniments in the chords of D, E, G, A, C, A $\sharp$, D $\sharp$, and F, as indicated in ascending order at the left-hand or bass side of the instrument. On the right-hand or treble side of the instrument will be found the treble chords to correspond with these bass-chords, and also additional beaters 30 for playing partial or intermediate chords.

In using the instrument it is placed on the 35 floor in front of the performer with the pedals in convenient reach of the feet. The cords from the beaters to the pedals are then arranged according to the key in which the accompaniment is to be played. For instance, 40 if the accompaniment is to be played in the key of D the pedals are so connected with such beaters that when they are depressed the chords D, A and G can be sounded as desired. Having thus arranged the instrument it is 45 evident that by placing the feet alternately upon the pedals of the treble and of the bass beaters not only can the proper chords be struck to harmonize with the music being played upon the main instrument, but they

can be beaten or operated in perfect time. 50 By means of the partial or intermediate cords suitable changes can be made by operating the respective pedals when necessary. If it is desired to play an accompaniment in another key, the cords of the beaters that will not be used are disconnected from their pedals and those from beaters which will be used are substituted. 55

By making the instrument as above described it occupies but small space and the 60 case can be made as ornamental as desired, and can easily be carried from place to place and thereby enable a single performer to produce very sweet and melodious music. By arranging the beaters so as to operate 65 keys or openings it is evident that the mechanism could be adapted for use upon wind-instruments, as an organ, by providing wind-chests and reeds instead of strings.

Having thus described my invention, I 70 claim—

1. The combination, with a case, of a musical instrument secured therein, boards adjacent to the instrument, one side of which boards is provided with beaters pivotally 75 secured thereto, and the other side is provided with a series of hooks, there being a hook for each beater, pedals secured in the case, and cords secured to the beaters, and adapted to be secured to the pedals or to the 80 hooks upon the boards, substantially as set forth.

2. The combination, with a case, of a musical instrument secured therein and provided with strings, rock-bars which are pivoted in suitable bearings, beaters mounted on said rock-bars, two or more of said beaters, having arms of different lengths, being mounted on the same rock-bar, so as to strike different strings, and mechanism for actuating 85 said beaters, substantially as and for the 90 purposes described.

In testimony whereof I have affixed my signature in presence of two witnesses.

SAMUEL BLACKETER.
